UNITED STATES PATENT OFFICE.

HAROLD ROUNTREE, OF KENILWORTH, ILLINOIS, ASSIGNOR TO NATIONAL PNEUMATIC COMPANY, OF NEW YORK, N. Y., A CORPORATION OF WEST VIRGINIA.

COMBINED CAR SIGNAL AND CONTROL APPARATUS.

1,184,134.

Specification of Letters Patent. Patented May 23, 1916.

Application filed October 17, 1913. Serial No. 795,652.

To all whom it may concern:

Be it known that I, HAROLD ROUNTREE, a citizen of the United States, residing at Kenilworth, county of Cook, State of Illinois, have made a certain new and useful 5 Invention in Combined Car Signal and Control Apparatus, of which the following is a specification.

This invention relates to car signal apparatus.

The object of the invention is to provide a car signal apparatus wherein means are provided which are controlled by the elevator inclosure doors for rendering the car 15 hoisting means inoperative to start the car when any inclosure door is open, while at the same time, a signal device on the car is placed in condition to be operated when desired to do so.

20 A further object of the invention is to provide a signal device on the car which is inoperative when all the inclosure doors are closed, in combination with controlling devices for the car hoisting motor, and means 25 whereby when a door is open the car hoisting motor is rendered inoperative while the signal device is placed in condition to be operated when it is desired to do so.

A further object is to provide means 30 whereby when the car is at any floor or landing the mere closing of an electric circuit will either start the car in case the apparatus is in condition therefor, or will cause a signal to be made if the apparatus 35 is not in condition for the car to start.

Other objects of the invention will appear more fully hereinafter.

The invention consists substantially in the construction, combination, location and relative arrangement of parts, all as will be 40 more fully hereinafter set forth, as shown in the accompanying drawing, and finally pointed out in the appended claims.

The single view of the drawing shows diagrammatically an arrangement of signal and control apparatus embodying my invention.

In the practical operation of elevator cars, and particularly automatically controlled 50 elevator cars of the dumbwaiter type, it is customary to provide a signal device, either visual or audible, which, in some arrangements, is made manifest whenever an inclosure door is opened, and continues as long as the door remains open. In elevator 55 cars of the automatic dumb-waiter type the

car hoisting motor is controlled, according to one system, from a central station, through a push button arrangement containing as many push buttons as there are floors at which the elevator is to stop. By manipulating any desired button the motor is put into operation and the car is caused to travel to the floor corresponding to the push button which has been manipulated, and upon reaching that floor the car stops automatically. An attendant at that floor thereupon opens the inclosure door which action cuts out the hoisting motor and hence prevents the car from starting until the door is again closed, and when the door is closed 60 the attendant at the control station is then able to cause the car to return to the initial starting point, or to proceed to any other floor. This is called the "one point" control system. In another type of automatic cars an 65 attendant at any floor may, by manipulating a push button at that floor, cause the car hoisting motor to start up and the car to proceed to that floor and then come to rest. In this system the inclosure doors also control 70 the starting operation of the hoisting motor in such manner that so long as an inclosure door is open the car hoisting motor controller is rendered inoperative. In both 75 systems it has been customary, as above 80 stated, to employ a signal device which is rendered operative when an inclosure door is opened and which continues in operation as long as the door remains open. It may happen that an attendant at a floor may 85 negligently leave the elevator inclosure door open even after the purpose for which the car was sent to that floor has been fulfilled, in which event the signal will continue to 90 operate. And even during the time the car 95 remains at a floor with the adjacent inclosure door open the signal remains in operation and the car hoisting motor cannot be put into operation. It is objectionable for 100 the signal to thus remain in operation and it is among the special purposes of my invention to avoid the same.

In carrying out my invention, I propose to provide a controller for the car hoisting motor, and also a signal device, and a switch 105 device which is associated in the circuits of both the controller and the signal device and controlled by the inclosure doors in such relation that when any inclosure door is open the signal device but not the motor con- 110

troller is rendered operative, and when all the inclosure doors are closed the motor controller but not the signal device is rendered operative. In other words I propose to provide a switch which, if desired, may be in the form of a push button, and to locate the same at or in convenient relation to the controlling station, and to place said switch, or push button in the circuit both of the signal device and of the motor controller whereby, by closing said circuit the motor controller will operate to cause the motor to return the car to the starting point provided the hatchway door opposite the car is closed, but if said door is open then the closing of said switch, instead of affecting the motor controller, will cause the signal to operate, and in case the signal is operated when said switch is closed the signal will continue to operate as long as the switch remains closed provided the hatchway door also remains open, or the signal may be operated periodically, if desired, so long as the door remains open, to attract the attention of the attendant at the floor where the car has stopped. When the door is closed, however, the signal device is rendered inoperative and then, by closing the same switch the motor is operated to cause the car to return to the starting point.

In the drawing I have illustrated an arrangement embodying the principles of my invention and wherein A, is the car, B, the hoisting motor therefor, C, the signal device, which, in this instance is placed on the car, D, the controller for the hoisting motor, E, the inclosure doors, and F, the door switches, each adapted to be opened when its associated door is open and to close when said door is closed. These parts may all be of the usual and well known construction and arrangement of automatic dumbwaiter systems and require no special description. The ordinary operation is simple. When the motor controller D, is operated in response to the manipulation of one or another of the push buttons G, the motor starts up and causes the car to travel to the floor or landing corresponding to the particular button G, which has been manipulated, and when the car reaches that floor, it automatically comes to a stop. The various operations required to effect these results are well known and in extensive use and they require no further illustration or description herein as, in the details thereof, they form no part of my present invention. The illustration of the controller D herein is merely conventional and is not designed to show the entire details thereof.

When the car comes to rest at a landing or floor, the adjacent inclosure door is opened and the attendant proceeds to load or unload the car.

65 The circuit of the door switches includes

a magnet H, said circuit being closed and the magnet H, energized in any suitable manner and from any convenient source whenever all the inclosure doors are closed. The door switches F, are arranged in series 70 in the circuit of the magnet H, so that when any door E is opened thereby opening its corresponding switch F the circuit of magnet H is opened and said magnet becomes de-energized. The magnet H, controls a mov- 75 able armature J, which is connected to one terminal of the circuit of the push buttons G. The armature J, also works between contact points K, L, so that when the magnet H is energized the armature makes con- 80 nection with contact L, and when the circuit of said magnet is open said armature makes connection with the contact K. The contact K is connected to one terminal of a source of current, conventionally shown as 85 a battery M, while the contact L is connected to one terminal of another source of current conventionally illustrated as a battery P. The signal device C, is connected on one side to the other terminal of current 90 source M, and the controller D is connected on one side to the other terminal of current source P. On their other sides the signal device C and the controller D are both connected to the same switch device, shown as a 95 push button N, in the circuit of armature J.

In the drawing the magnet H is shown as de-energized, that is an inclosure door E at some point in the elevator well is supposed to be open, thereby opening its adjacent switch F, and hence opening the circuit of the magnet H. Under this condition the armature J is contacting with contact K, and is out of contact with contact L, and consequently the circuit of controller 100 D cannot be completed to current source P, through switch N, and said controller cannot be operated. But the signal circuit which includes in series the current source M, contact K, armature J, the push button 110 N, and the signal C, is rendered operative, so that by manipulating the button N, the signal circuit is completed and the signal is operated. Suppose however, that all of the inclosure doors are closed. Thereupon the 115 circuit of magnet H is completed and said magnet is energized. This causes the armature J to be brought into connection with contact L and to break connection with contact K. Thereupon the signal circuit is rendered inoperative when switch N is closed, since circuit connection to source M is broken, but the circuit of the controller device D may now be completed from current source P through contact L, armature J, 120 any one of the push buttons G, or switch N, to ground or return, thereby causing the motor B to start up and move the car to the floor corresponding to the particular push button G which was manipulated, or to re- 130

spond to the manipulation of push button N. This button may be employed to cause the car to return to the starting point. Thus it will be seen that the magnet H controls both the signal device circuit and also the circuit of the controller D, in such manner that when the one is in condition to be operated through push button N, the other is not. It will also be seen that with this arrangement if an attendant causes the car to remain too long at a floor through failure to close the inclosure door at that floor, his attention may be called to the neglect by operating the signal device C, and that said signal device need not be in continuous operation all the time the door remains open.

It will be understood, of course, that the push buttons G, N, may correspond, respectively to the various floors at which the car is to stop, and consequently by pushing any one of them, if the conditions are right the car will start up and travel to the particular floor determined by the particular button that has been manipulated and will stop at that floor.

Having now set forth the object and nature of my invention and a construction and arrangement embodying the principles thereof, what I claim as new and useful and of my own invention, and desire to secure by Letters Patent is:

1. In a combined car signal and control apparatus, a car, a signal, a switch for operating the same, an inclosure door, a car hoisting motor, and gravity actuated means controlled by the inclosure door for rendering the motor inoperative, and rendering the signal operative when the door is open and the switch is closed.
2. In a combined car signal and control apparatus, a car, a signal, a switch for operating the same and inclosure door, a car hoisting motor, and means controlled by the inclosure door for rendering the signal operative and rendering the motor operative when the door is closed and the switch is closed.
3. The combination with a car, a hoisting

motor therefor, a controller for the motor, a signal device, circuits for the controller and signal device, a switch operating to control both circuits, inclosure doors, and means controlled by the opening and closing of the inclosure doors for controlling said switch.

4. The combination with a car, a hoisting motor therefor, a controller for the motor, a signal device, circuits for said signal device and controller, a switch device for controlling both circuits, and operating to open one when it closes the other, a magnet for controlling said switch, means for controlling the magnet circuit and an auxiliary switch in both of said circuits.

5. In a combined car signal and motor control apparatus, a motor control circuit and a signal circuit, a switch for controlling both circuits, said switch operating to open one when it closes the other, a magnet for operating said switch in one direction, a circuit therefor, door switches in series in said magnet circuit and an auxiliary switch for controlling said control and signal circuits.

6. The combination with a motor circuit and a signal circuit, a switch for controlling both circuits and operating to open the one when the other is closed, means operated by the opening or closing of a door for operating said switch and an auxiliary switch for controlling both of said circuits.

7. The combination of a car, a hoisting motor therefor, means for causing the car to start to travel to any predetermined floor, an inclosure door, a signal, and gravity actuated means controlled by the inclosure door for rendering the starting means operative to operate the signal and inoperative to start the hoisting motor when the door is open.

In testimony whereof I have hereunto set my hand in the presence of the subscribing witnesses on this 8th day of October A. D., 1913.

HAROLD ROWNTREE.
